ELECTRIC CONNECTER

Robert A. Meeker, Chicago, Ill.

Application September 4, 1934, Serial No. 742,562

1 Claim. (Cl. 173—303)

The present invention relates generally to electrical connectors. More particularly the invention relates to that type of connector which is designed to connect together a pair of electrical conductors for the transmission of current from one conductor to the other and comprises (1) an elongated body which embodies means at one of its ends for attachment to the free end of one of the conductors and has an internally threaded, longitudinally extending bore in the other end thereof; (2) an outwardly tapered, longitudinally split sleeve which is designed to surround the free end of the other connector and is adapted after being sleeved over the last mentioned conductor to be inserted into the internally threaded bore in the body; and (3) a sleeve type nut which is provided with an external screw thread for engaging the internal screw thread in the bore of the body and has the bore thereof tapered correspondingly to the sleeve so that when it is screwed into the body it operates to contract the sleeve and jam it around the conductor.

One object of the invention is to provide an electrical connector of this type in which the body is provided at the inner end of the internally threaded bore with a polygonal socket and the sleeve is provided at its inner end with a polygonal head which, when the sleeve is in place in the bore, fits within the socket and coacts with the latter to hold the sleeve against rotation relatively to the body.

Another object of the invention is to provide an electrical connector of the last mentioned character in which the sleeve portion of the nut is split longitudinally and as a result is expanded into locked relation with the body when the nut is screwed into place.

A still further object of the invention is to provide an electrical connector which not only may be manufactured at a low and reasonable cost but also is an improvement upon and is more efficient than previously designed electrical connectors of the same general type.

Other objects of the invention and the various advantages and characteristics of the present electrical connector will be apparent from a consideration of the following detailed description.

The invention consists in the several novel features which are hereinafter set forth and are more particularly defined by the claim at the conclusion hereof.

In the drawing which accompanies and forms a part of this specification or disclosure and in

which like numerals of reference denote corresponding parts throughout the several views:

Fig. 1 is a view partially in section and partially in elevation of a connector embodying the invention;

Fig. 2 is a longitudinal section of the body of the connector;

Fig. 3 is a perspective of the outwardly tapered split clamping sleeve, which is adapted to fit in the fore of the connector body and serves securely to clamp or retain the conductor in the body;

Fig. 4 is a longitudinal section of the sleeve;

Fig. 5 is a perspective of the sleeve type nut for securing the sleeve in the body of the connector; and

Fig. 6 is a longitudinal sectional view through the nut.

The connector which forms the subject matter of the invention is adapted to connect together a pair of electrical conductors 15, 15^a for the transmission of current from one conductor to the other and comprises a body 10 which is formed of electrolytic copper and has a polygonal outer periphery so that it may be held against turning by a wrench while the various parts of the connector are being joined together. This body is provided at one end thereof with an internally threaded bore 11 into which the free end of the conductor 15 is adapted to be inserted. The inner end of this bore terminates in an inwardly tapered hexagonal socket 12. The central portion of the body has an integral cross-wall 14.

The bore 11 is adapted to receive a sleeve 16, 35 the inner end of which has a head 17. The latter is hexagonal in conformation, as shown in Figs. 3 and 4, and is tapered correspondingly to, and adapted to fit within, the tapered hexagonal socket 12 in the body 10. One side of the sleeve 40 16 is formed with a split 18 extending from end to end and at its other side the sleeve is formed with a split 19 which extends inwardly from the outer end of the sleeve and terminates outwardly of its inner end so that the sleeve will 45 be contractible and all portions thereof will be integral. The bore of the sleeve 16 is formed with an internal screw thread 20 extending from end to end to provide a formation which will bite into the conductor 15 when the sleeve is contracted. The purpose of forming the sleeve with a tapered head 17 which fits into the correspondingly shaped socket 12 in the connector body is to cause the sleeve to be interlocked 50 against rotation relatively to the conductor body 55

10 when the sleeve is inserted in the body. The outer periphery of the sleeve 16 is conoidal or tapered from its inner end outwardly.

- In addition to the body 10 and the sleeve 16, 5 the connector embodies a sleeve type nut (see Figs. 5 and 6). This nut comprises a sleeve portion 21 having an external screw thread 22 which fits the internal screw thread in the bore 11 of the connector body. The nut also comprises an 10 enlarged head 23 which is at the outer end of the sleeve portion 21 and has a hexagonal portion 24 so that a wrench may be applied to the nut. The sleeve portion 21 of the nut is longitudinally slotted as at 25 from its inner end to 15 the head 23 so that it is expandable. The nut has a bore 26 which tapers outwardly from its inner end to conform to the taper on the sleeve 16 so that as the nut is screwed into the body 12 the sleeve portion 21 will be expanded against 20 the screw thread in the bore 11 and simultaneously the sleeve 16 will be contracted to force the thread 20 in the sleeve into the conductor. The tapered bore 26 of the nut extends outwardly beyond the sleeve to a point 27 where 25 the diameter corresponds substantially with the diameter of the conductor and beyond the point 27 the bore of the nut is flared slightly as at 28. This formation in the bore of the nut provides a substantial fit between the conductor and the 30 nut outwardly of the sleeve 16 where there is no clamping or jamming effect produced on the conductor. The purpose of this formation is to support the conductor at a point outwardly of the sleeve. In practice it has been found that 35 crystallization causes the conductor to fracture at the point where the jamming terminates, if the cable is left unsupported beyond the point where the jamming of the sleeve 16 terminates. By providing the aforementioned formation between the nut and the conductor the latter is supported outwardly of the portion of the cable which is jammed in the sleeve and hence vibration which causes fracture from crystallization 40 is overcome.
- 45 To connect the conductor 15 to the connector body 10, the sleeve 16 is first passed through the bore 11 until the head 17 is seated in the hexagonal socket 12 in said body. The taper of the head 17 of the sleeve facilitates the entry of the sleeve into the socket 12. When the sleeve has 50 been thus placed in the body 10 it is in its normal expanded condition and is locked against rotation relatively to the body 10. The nut 23 is then slipped over the free end of the conductor 15 and the latter is slipped into the sleeve 16 in the body 10 until the end of the conductor engages the cross wall 14. At this time the conductor 15 will pass freely into and through the sleeve 16 because the latter is not contracted. 55 Next the screw threaded sleeve portion 21 of the nut is screwed into the socket 11 by applying a wrench to the hexagonal portion 24 of the nut. Rotation of the nut will cause the sleeve portion 21 with its tapered bore to be forced inwardly around the sleeve 16 and the engagement of the tapered bore 26 of the nut with the correspondingly tapered outer periphery of the sleeve 16

will cause the sleeve to contract so that the screw thread 20 in the sleeve 16 will bite into the conductor. Simultaneously the wedging action between the sleeve and the nut will cause the split sleeve portion 21 of the nut to be jammed in the bore 11 of the connector body 10. After the nut has been screwed into the body as far as possible the conductor 15 is securely joined to the connector body 10. When it is thus joined the outer portion of the nut will support the conductor 15 outwardly of the outer end of the sleeve 16 where the conductor is jammed so that the conductor will be supported against vibration at the point where the jamming terminates and so that crystallization will not cause the conductor to break adjacent the outer end of the sleeve.

As a result of jamming the screw thread 20 of the sleeve 16 into the conductor with the thread interrupted at the splits 19 and 20, the conductor 15 will not be rotatable in the sleeve when the latter has been contracted. This results from using a split sleeve end interlocked between the sleeve and the body to prevent relative rotation. By employing a split sleeve portion on the nut 21 and a split sleeve the nut will in effect be locked in place when it has been turned into the body to secure the conductor in the sleeve.

The conductor 15 is secured to the opposite end of the connector body 10 by means of a 30 sleeve, and sleeve type nut which correspond respectively with the sleeve and nut for the conductor 15.

The herein described connector is extremely efficient in operation and may be produced at a 35 low and reasonable cost. It may be reused and the parts thereof are so constructed and formed that it may be assembled quickly and easily.

The invention is not to be understood as restricted to the details set forth since these may 40 be modified within the scope of the appended claim without departing from the spirit and scope of the invention.

Having thus described the invention, what I regard as new and desire to secure by Letters 45 Patent, is:

As a new article of manufacture, a connector for an electrical conductor, comprising an elongated body having an internally threaded bore in one end thereof and a polygonal socket at the 50 inner end of the bore, a longitudinally split one piece sleeve for the conductor designed to fit within the bore and having its outer periphery tapered from the inner end thereof to its outer end and also having a polygonal head at its 55 inner end adapted to fit within the socket and shaped conformably to the latter so that it contacts therewith to hold the sleeve against rotation relatively to the body, and a nut embodying a longitudinally slit sleeve portion with an external 60 screw thread for engaging the internally threaded bore, and having an outwardly tapered sleeve-receiving bore whereby when the nut is screwed into the body the sleeve portion is expanded into locked relation with the body and the sleeve is 65 contracted around the conductor.

ROBERT A. MEEKER.
